UNITED STATES PATENT OFFICE.

ERNEST J. SWEETLAND, OF MONTCLAIR, NEW JERSEY.

METHOD OF DEVELOPING PHOTOGRAPHIC SENSITIZED FILMS.

Application filed July 21, 1919. Serial No. 312,258.

To all whom it may concern:

Be it known that I, ERNEST J. SWEETLAND, a citizen of the United States, residing in the town of Montclair, county of Essex, and

5 State of New Jersey, United States of America, have invented certain new and useful Improvements in Methods of Developing Photographic Sensitized Films, of which the following is a specification.

10 This invention relates to a novel method of handling and manipulating a photographic film whereby the same may be developed in an exceedingly simple yet thoroughly safe and efficient manner.

15 Two principal objects are achieved by the present invention. One of these objects is to obtain the utmost simplicity in the handling of the film whereby the method or process may be readily practiced by amateurs or unskilled persons, and the second principal object is to provide a way of handling, manipulating and protecting the sensitized film to thereby insure a thorough and uniform development of the film throughout 20 its entire extent while at the same time facilitating the washing and fixing operations without danger of light exposure until the film may be handled in the open light.

Another object of the invention is to provide 25 a method of development for a sensitized film which is especially available for the so-called daylight film development, and which may be carried out with no apparatus other than a protecting and covering "developing bag," such as disclosed in my former Patent No. 1,285,462, dated November 19, 1918, and co-pending application, Serial No. 267,609, filed December 20th, 1918.

Though various mechanical devices and 30 expedients may be utilized in carrying forward the present method, the preferable apparatus, however, employed to facilitate the various operations, is shown in the accompanying drawings, in which:—

45 Figure 1 is a sectional view of a collapsible developing bag with the film spool and the two hands of an operator shown in the operative position that they occupy while the film is being unspooled.

50 Figure 2 is a top plan view of the apparatus shown in Figure 1, with the top side of the bag shown broken away to expose therein the film spool with the "duplex" paper strip being drawn in one direction, while 55 the sensitized and exposed film is held by the clip or other holding means.

Figure 3 is a view of the apparatus in the position it takes with the film strip extended and flattened out for developing, washing and fixing operations.

60

Figure 4 is a view of the apparatus in the same condition as shown in Figure 3, excepting that the open end portion of the bag is turned up to illustrate how the liquid may be poured into and discharged from the bag.

65

Figures 5, 6 and 7 are detail views showing a form of the apparatus in which the bag may be fitted with a filler tube to facilitate the operations employing the liquids for developing the film and for fixing and washing the negative.

70

Corresponding and like parts are referred to in the following description and indicated in all the views of the drawings by the same reference characters.

75

A distinctive feature of the present invention resides in the method of handling and manipulating a film spool within a developing bag or chamber whereby the sensitive exposed film may be unspooled by the act of drawing out the paper strip in a direction opposite and away from the film.

80

In explanation of the unspooling operation referred to particular reference may be had to Figures 1 and 2 of the drawings, wherein is shown the flexible and collapsible rubber tube 1 herein termed the developing bag. This developing bag is closed at one end as at 2, and the opposite open end portion 3 thereof is adapted to be gathered over one arm and wrist of the operator to provide a light-tight closure at the open end of the bag, while at the same time permitting the same to be paid-out to the necessary length as the sensitized film is unrolled. In these

95

particulars, the device 1, which constitutes the developing bag, is similar in construction and function to the corresponding device shown in my former Patent No. 1,285,462, but, as indicated, the unspooling operation is accomplished by utilizing a holding clip 4 to engage one end of the film 5 and a drawing clasp 6 adapted to engage the end of the paper strip 7, which, together with the film 5 are rolled or wound upon a single spool 8. A pull cord or chain 9 attached to the clasp 6 facilitates the fingers of the hand inserted in the developing bag engaging with either the pull element 9 or the clasp 6 to provide for drawing the same in a direction toward and through the open end of the bag while the holding clip 4 is

100

105

110

- located within the closed end portion of the bag and is held between the fingers of the other hand of the operator on the outside of the bag. Thus, with the parts so related, 5 the sensitized film can be readily unspooled from the spool 8 by the act of drawing the paper strip 7 out toward and through the closed end portion of the developing bag. After this has been accomplished and the 10 film held in an extended position the operation of developing can be carried on within the bag without any danger of the film becoming light struck until it is ready to be removed from the bag.
- 15 In order that the various operations involved in the handling and manipulation of the film spool may be more fully appreciated and understood, reference will now be made to some of the steps of the method 20 which should be particularly and carefully observed in following out the same. First, after breaking the seal of the "exposed" film under the exercise of proper care and not unrolling the paper sufficiently to admit 25 light to the end of the exposed film, the drawing clasp 6 is attached to one end of the paper strip 7 and the holding clip 4 is attached to that end of the film which is not sensitive and simply the end portion of 30 the film which holds the film in proper position in the camera, that is to say—the "dead" end of the film is engaged by the holding clip 4.

After attaching the clasp 6 and the clip 4 respectively to the paper strip 7 and to the end of the film 5, the film spool and clip are placed in the bag with the right hand and with the left hand the bag is gathered up on the wrist and forearm until the 40 clip and spool reach the bottom or closed end of the bag, after which the clip is engaged between the fingers of one hand and the pull cord or chain or drawing clasp 6 are engaged by the fingers of the inserted 45 hand, as readily shown in Figure 1 of the drawing, so that the act of pulling out the paper automatically unrolls the film and spreads it out in the bag.

The drawing upon the paper strip 7 is 50 continued until a few inches of the paper protrude from the bag, and then a light weight is placed on the bag near the open end, thus keeping the mouth of the bag closed against the table while the paper is 55 withdrawn from the slit formed by the lips of the bag. In the meanwhile the left hand rests on top of the bag back of the spool and prevents the film from slipping, and the operator continues to pull out the paper 60 until there is felt a sudden stop which occurs when the spool has almost reached the mouth of the bag, and this stop occurs because the end of the film is attached to the 65 paper strip. It is now necessary to hold the left hand firmly on the bag and its enclosed

film so that the film cannot slip out and the paper is pulled so as to detach the same from the film and thereby permit the spool and paper to be removed. In these operations, the film should be "right side up"; 70 that is, sensitized side up, in the bag.

The advantages accruing by reason of the removal of the paper from the bag prior to development are important. A smaller quantity of developing solution may be used, 75 thus effecting economy in the use of the bag. The developing solution is maintained in a clearer state, after once being used, thus enabling its repeated use, since the liability of the solution becoming contaminated by impurities in the paper, such for instance as soluble salts, might re-act unfavorably with the developing solution or the chemicals used in preparing the film. Furthermore, where "autographic" variety 80 of film is used, agitation of the developing solution within the bag has a tendency to disintegrate the autographic tissue, thus causing particles of the paper to mix with the solution and render it unfit for further 85 use. These objectionable characteristics are entirely obviated by the removal of the paper according to my method of development so that the solution is maintained in a state which renders it repeatedly useable if de- 90 sired.

When the removal of the paper strip has been accomplished, with the film in its extended condition, shown in Figure 3, the open end of the bag is folded even with the 100 end of the film and a second outside retaining clip 10 applied to serve the double purpose of holding the film securely in position and forming a light-proof closure for the end of the bag. However, it will be ob- 105 served that the said retaining clip 10 does not extend entirely across the width of the bag, but is disposed at one side of one edge portion of the bag, thereby forming a light- 110 proof closure and at the same time leaving a lateral liquid passage-way 11 through the end of the bag at one side thereof, as shown in Figure 4 of the drawings. This passage-way permits the water or developer to pass in or out freely while filling or draining the 115 bag. In the normal developing position, the open end of the bag folds back over the clip 10, as shown in Figure 3, and the solution will not run out, as the fold maintains part of the end of the bag at a higher level 120 than the level of the solution in the bag. Usually the clip 10 only extends about half-way across the bag to leave a well defined passage-way 11 which may be utilized, with the open end portion of the bag in the position 125 shown in Figure 4, for the filling operation, and, for the draining operation the entire bag may be held by both hands in a straightened out position and canted to drain out the liquid through the passage-way 11. These 130

are of course details in the handling of the bag for the developing, fixing and washing operations, detailed instruction for which will be furnished by the manufacturer.

- 5 The present invention involves no change in the use of the developing and fixing solutions, but of course provides a novel way of employing these solutions in connection with a sensitized film which is held in strip form 10 in a collapsible developing bag, and in this connection it will be observed that other ways of introducing the liquids into the bag and draining the same therefrom may be resorted to without departing from the present invention. For instance, as suggested in Figures 5, 6 and 7 of the drawings, the bag may have fitted thereto at or near the closed end portion thereof a filler tube 12 through which the liquids may be introduced. This 15 20 filler tube may be closed when not needed by a closing clip or clasp 13, and when in use a funnel 14 may be used to introduce the liquid, and for washing operations the spigot 15 may be directly connected with the tube 12, and the stream passed through the bag and out at the other end.

While I have illustrated and described certain instrumentalities, such as the clip and clasp, which may be usefully employed 30 in carrying out or practicing of the invention, these are mere conveniences and their use may be discarded since a skillful operator can practice the invention wholly by hand, manually unrolling the film in the bag 35 and holding it in proper position therein during the entire operation by the use of his hands only.

From the foregoing it is thought that the novel method of manipulating and developing the film will be readily understood without further description.

Having thus described my invention what I claim as new herein and desire to secure by Letters Patent is:

- 45 1. The method of developing photographic film, which includes the step of unrolling a film from the spool within a light-proof container by holding the free end of the film against movement and leaving the spool free 50 to move bodily while the covering protecting paper of the film is being withdrawn from the spool, thus causing the spool to rotate and move bodily in the direction of movement of the paper.

- 55 2. The method of developing photographic film, which includes the step of placing the

roll of film in and near the bottom of an elongated light-proof bag by gathering the bag over the fore-arm, then unrolling and straightening the film within the bag by 60 holding the free end of the film securely between the walls of the bag, while the covering paper is being unrolled and withdrawn from the spool as the bag is being extended to normal position.

65 3. The method of developing photographic film which includes the step of unrolling a film from a spool free to move bodily within a light-proof container and simultaneously removing the protecting paper from the film 70 by drawing on the paper and thereby effecting a bodily movement of the spool with respect to the container.

75 4. The method of developing photographic film, which consists in placing a roll of film within a light-proof container, holding the free end of the film stationary, and drawing on the protecting paper and thereby moving the spool bodily in a direction away from the stationary end of the film and unrolling 80 the film from the spool and simultaneously removing the protecting paper from the film.

85 5. The method of developing photographic films, which consists in manually unrolling the film from a bodily movable spool positioned within a light-proof container by drawing upon the paper strip on the spool while one end of the film is held stationary, and subsequently introducing the developing 90 solution into the container.

95 6. The method of developing photographic films, which consists in unrolling the film from its spool within a light-proof extensible bag by holding one end of the film stationary and drawing out the paper strip on the spool in the direction of and simultaneously with the extension of the bag, and subsequently introducing the developing solution into said bag.

100 7. The method of developing photographic films, which consists in manually unrolling a film from its spool within a light-proof extensible bag by holding the end of the film stationary within one end of the bag and drawing upon the paper strip on the spool in the direction of and through the opposite end portion of the bag, and subsequently introducing the developing solution into said bag with the film strip extended therein.

ERNEST J. SWEETLAND.
